Primary Examiner—Cathron C. Brooks

(74) Attorney, Agent, or Firm—Emerson & Skeriotis;
Roger D. Emerson; Daniel A. Thomson(57) **CLAIM**

The ornamental design for a plastic closure, as shown and described.

DESCRIPTION

FIG. 1 is a perspective view showing the new design;
 FIG. 2 is a second perspective view thereof;
 FIG. 3 is a side elevational view taken from the right of FIG. 1;
 FIG. 4 is a front elevational view thereof;
 FIG. 5 is a back elevational view thereof;
 FIG. 6 is a bottom plan view thereof; and,
 FIG. 7 is a top plan view thereof.
